UNITED STATES PATENT OFFICE

ALFRED B. ESSELTINE, OF CHICAGO, ILLINOIS, ASSIGNOR TO GOODMAN MANUFACTURING COMPANY, OF CHICAGO, ILLINOIS, A CORPORATION OF ILLINOIS

MINING MACHINE

Application filed April 16, 1930. Serial No. 444,679.

This invention relates to improvements in mining machines and more in particular to machines of the type adapted to remove the material cut away from the face of the coal and load it into a suitable receptacle or material transporting device, and has among other objects to provide such a machine especially adapted for use in driving entries having a new and improved form of conveyor thereon which may be fed into the kerf with the cutter bar and is of substantially the same vertical dimensions as the cutter bar and which may support and convey the mined material beyond the mining machine proper.

Other objects of my invention will appear from time to time as this specification proceeds.

My invention may be more clearly understood with reference to the accompanying drawings wherein:

Figure 1 is a top plan view of the device embodying my invention with parts broken away and in section;

Figure 2 is a side elevation of the device shown in Figure 1 with parts broken away and in section;

Figure 3 is an enlarged partial sectional view taken on line 3—3 of Figure 1;

Figure 4 is an enlarged partial fragmentary front end view of the device embodying my invention with parts broken away and in section;

Figure 5 is an enlarged detail view of the rearward portion of the conveyor with parts broken away and in section;

Figure 6 is an enlarged detail view of the conveyor, looking forwardly of the machine;

Figure 7 is a diagrammatic side elevation of the machine after the cutter bar has completed the cutting of a kerf in the mine wall; and

Figure 8 is a diagrammatic side elevation of the machine showing the cut material shot down and supported on the cutter bar and conveyor.

Referring now in detail to the drawings, the device embodying my invention comprises a stationary frame 10 having a movable frame 11 supported thereon for longitudinal

movement with respect thereto which movable frame has a relatively wide horizontal cutter bar 12 projecting forwardly therefrom having a cutter chain 13 movable thereabout.

The stationary frame 10 comprises a pair of parallel spaced longitudinally extending guide members 14, 14 supported at their rearward ends above the mine bottom and substantially parallel therewith on a supporting frame member 15, and supported on a shoe 16 at their forward ends. The shoe 16 extends the entire width of the machine and serves as a guide for the cutter bar 12. A roof jack 17 is attached to the top portion of one of the guide members 14 to hold the stationary frame 10 in a stationary position with respect to the mine wall during the cutting operation.

A rack 18 of an ordinary construction is fixed on the outer side of each guide member 14 and each rack 18 is engaged by a sprocket 19 on the opposite ends of a transverse shaft 20 journaled on the movable frame 11 for moving said movable frame along the stationary frame 10 upon rotation of said sprockets and shaft.

The movable frame 11 is slidably supported on the top portion of the parallel spaced guide members 14, 14 and depends therefrom so the cutter bar 12 may cut a kerf adjacent the mine bottom, and supports the feeding and drive mechanism for the cutter chain 13.

The cutter chain 13 is driven about the cutter bar 12 by means of a suitable power device herein preferably shown as an electric motor 22, through a suitable gear train which comprises a motor pinion 23, idler gear 24, spur gear 25 on the rear end of a longitudinal shaft 26, bevel pinion 27 on the forward end of said shaft, bevel gear 28 freely mounted on a vertical shaft 29 and sprocket 30 on the lower end of said vertical shaft operatively connected with said bevel gear by means of a jaw clutch 31 in a usual manner.

Referring now in particular to the means for driving the sprockets 19 from the motor 22, a worm 34 is cut integral with the longitudinal shaft 26 and drives a worm gear 35

keyed on a sleeve 36 freely mounted on the transverse shaft 20. The sleeve 36 drives a frictionally controlled plural speed planetary gear reduction device 37 of an ordinary construction which will only be described in so far as is necessary to fully disclose my present invention.

The planetary reduction device 37 comprises an internal gear 38 controlled by a friction band 39 having bearing engagement with a drum 40 integral with the outer periphery of said internal gear and driven from the sleeve 36 by means of a sun gear 41 integral with the sleeve 36 and planetary pinions 42 carried in a cage 43. Planetary pinions 44 are integral with and adjacent the planetary pinions 42 and mesh with and drive an internal gear 45. Clutch jaws 46 are provided on the internal gear 45 while clutch jaws 47 are provided on the cage 43. A clutch sleeve 48 is feathered on the shaft 20 and has clutch jaws 49 thereon so said clutch jaws may mesh with either the clutch jaws 46 or 47 to drive the transverse shaft 20 at either a high or low frictionally controlled speed. The clutch sleeve 48 is moved along the transverse shaft 20 by means of a suitable system of levers of an ordinary construction not herein shown.

It may now be seen that the shaft 20 and sprockets 19 may be driven at a plurality of frictionally controlled speeds by means of the planetary reduction device 37 which is controlled by the friction band 39, and that when said shaft is rotated in one direction, the cutter bar 12 may be moved into the coal, and that when the motor 22 is reversed and the shaft 20 is rotated in an opposite direction the cutter bar may be withdrawn from the coal. Thus a frictionally controlled plural speed means is provided for moving the cutter bar 12 in, or withdrawing said cutter bar from the coal, which friction means is arranged to slip in case obstructions or hard spots are met with in the coal while the machine is cutting.

Referring now in particular to several other of the novel features of my invention, a conveyor 50 is provided which conveyor is mounted within the cutter bar 12 and with its forward portion contained within the vertical limits of said cutter bar.

The conveyor 50 is preferably made up of a plurality of sections, herein shown as three sections placed side by side within the cutter bar 12, each section of which comprises a continuous wire mesh belt 52 passing over a direction changing device 53 of relatively small diameter fixed in the forward portion of the cutter bar 12 and a conveyor frame 54.

It should be noted that the conveyor belts are made from wire mesh instead of rubber or composition belting or other materials from which conveyor belts are usually made

and that a plurality of relatively narrow belts are used instead of one wide belt to provide a conveyor which will withstand the heavy stresses imposed thereon when an entire coal wall is shot down on the mining machine and conveyor. These mesh conveyor belts are made from interwoven wires in a manner similar to which ordinary heavy duty woven wire fencing is made; that is, strands comprising a single wire extending transversely of the conveyor are each formed with open loops interwoven alternately with similar loops on the advance and following strand. These strands have rolling contact with said loops permitting maximum flexibility of the conveyor along transverse lines. This provides a conveyor belt which may be turned about a curve of a minimum radius and thus permits the construction of a thin durable conveyor capable of withstanding great loads and stresses having a total thickness of the top and bottom runs substantially equal to the thickness of the cutter bar.

The conveyor frame 54 includes a forward portion 54a contained within the cutter bar 12, an inclined portion 54b rearwardly of said forward portion and a rear horizontal portion 54c which extends over the motor 22 and is supported thereon on suitable supports 51, 51. The rear horizontal portion 54c of the conveyor frame 54 extends beyond the stationary frame 10 a sufficient distance so the rearward end of the conveyor 50 extends beyond the rearward end of the stationary frame 10 when the cutter bar 12 is dumped into the coal to its full depth.

The conveyor frame 54 is formed by guide strips 55 at each side of the conveyor 50 and on the outer sides of the outer wire mesh belts 52, and spacing strips 56 which separate each wire mesh belt 52 from the adjoining wire mesh belt. A supporting plate 57 separates the top and bottom runs of each wire mesh belt 52 and serves as a support for the top run of each of said belts. Guide plates 58 are provided on the top and bottom portions of the guide strips 55 and spacing strips 56 so each continuous wire mesh belt 52 is guided between the supporting plates 57 and guide plates 58 and guided on its sides by means of the guide strips 55 and spacing strips 56.

A space 60 is left between the outer side of each guide strip 55 and the inner sides of the cutter bar 12 for a distance equal to the length of the section 54a which space forms guides for the supporting shoe 16. See Figure 4 in which it may be noted that the shoe 16 extends for the entire width of the machine and is guided in the spaces 60 between the inner sides of the cutter bar 12 and the guide strips 55. This guide space forms a slidably supporting guide for the shoe 16 so the cutter bar 12 may be moved forwardly into the coal slidably supported on said shoe.

5 Each wire mesh belt 52 of the conveyor 50 is simultaneously driven from the motor 22 by means of a spur pinion 63 keyed on the sleeve 36 which spur pinion meshes with and drives a spur gear 64. The spur gear 64 has driving connection with a shaft 65 journaled in the conveyor frame 54 near the rearward end thereof by means of a suitable chain and sprocket drive generally indicated at 67.

10 Rollers 68, 68 are fixed on the shaft 65 and have studs 69 projecting outwardly therefrom which studs engage the continuous wire mesh belts 52 and drive said wire mesh belts upon rotation of the shaft 65.

15 It may thus be seen that a mining machine has been provided having a conveyor incorporated therewith which conveyor is made in sections to withstand heavy loads and which conveyor is also constructed of a plurality 20 of wire mesh belts so as to be able to turn about a member of relatively small diameter which enables said conveyor to be contained within the vertical dimensions of an ordinary mining machine cutter bar.

25 Figures 7 and 8 illustrate the use and operation of the machine embodying my invention. In Figure 7 the machine has been set adjacent the mine wall and the jack 17 has been set against the mine roof. The cutter bar 12 and conveyor 50 have been fed into the coal by means of the frictionally controlled sprockets 19 and the racks 18 and the coal is ready to be shot down on the machine and conveyor.

30 Figure 8 shows the coal shot down and supported on the mining machine and conveyor 50. After the coal has been shot down on the sectional wire mesh conveyor 50 the motor 22 is started and the material is moved 40 away from the coal face by said conveyor to a point beyond the rearmost extremities of the stationary frame 10 into a suitable receptacle or conveying device. As herein shown a draft operated scraper 70 is provided to move the material away from the mining and loading machine into a mine car or any other suitable conveying means for transporting the coal from the mine in a usual manner, although any other form of material handling means may be used to move the material from the conveyor 50.

35 Since the cutter bar 12 is relatively wide, and may be made in widths approaching the width of a mine entry, it may be seen that the machine of my invention is especially adapted for driving entries. The machine may be set in an entry and under cut the coal. The coal may then be shot down on the conveyor 50 and loaded into a suitable material transporting device. These operations may be continued until the entire entry is driven, thus providing a continuous system for cutting and loading in a mine entry.

40 While I have shown and described one form in which my invention may be em-

bodied, it will be understood that the arrangement or construction of the various parts may be altered or changed without departing from the spirit or scope of the invention. Furthermore, I do not wish to be construed as limiting myself to the specific embodiment illustrated, except as it may be limited in the appended claims.

70 I claim as my invention:

1. In a mining and loading machine, a stationary frame, a movable frame supported on said stationary frame for longitudinal movement with respect thereto, a relatively wide cutter bar supported on said movable frame and having a cutter chain movable horizontally thereabout, a direction changing device supported within said cutter bar of less diameter than the thickness of said cutter bar, and a continuous longitudinally extending wire mesh conveyor having a portion contained within the vertical and lateral limits of said cutter bar and extending around said direction changing device and another portion extending over and beyond the rearward extremities of said stationary frame when said cutter bar is in an extended position with respect to said stationary frame.

75 2. In a mining and loading machine, a stationary frame, a movable frame supported on said stationary frame for longitudinal movement with respect thereto, a motor on said movable frame, a relatively wide horizontal cutter bar supported thereon for movement therewith having a cutter chain movable horizontally thereabout, a direction changing device supported within said cutter bar of less diameter than the thickness of said cutter bar, and a continuous longitudinally extending wire mesh conveyor and extending around said direction changing device contained within the vertical and lateral limits of said cutter bar for a portion of its length and extending over said motor and beyond the rearward extremities of said stationary frame when said cutter bar is in an extended position with respect to said stationary frame.

80 3. In a mining and loading machine, a stationary frame, a movable frame supported on said stationary frame for longitudinal movement with respect thereto, a motor on said movable frame, a relatively wide horizontal cutter bar supported thereon for movement therewith having a cutter chain movable horizontally thereabout, a direction changing device supported within said cutter bar of less diameter than the thickness of said cutter bar, and a plurality of longitudinally extending continuous wire mesh conveyors arranged side by side and contained within the vertical and lateral limits of said cutter bar for a portion of its length and extending around said direction changing device and extending over and beyond the rearwardmost extremities of said stationary frame.

when said cutter bar is in an extended position with respect to said stationary frame.

4. In a mining and loading machine, a stationary frame, a movable frame slidably supported on said stationary frame for reciprocable movement therealong, a motor supported on said movable frame, plural speed means driven by said motor for reciprocably moving said movable frame along said stationary frame, a relatively wide horizontal cutter bar extending forwardly from said movable frame having a cutter chain movable thereabout, means for driving said cutter chain from said motor, a transversely extending direction changing member on the forward portion of said cutter bar within the vertical limits thereof, a wire mesh conveyor having a portion contained within the vertical limits of said cutter bar and passing around said direction changing member and means for driving said wire mesh conveyor from said motor.

5. In a mining and loading machine, a stationary frame, a movable frame slidably supported on said stationary frame for reciprocable movement therealong, a motor supported on said movable frame, plural speed means driven by said motor for reciprocably moving said movable frame along said stationary frame, a relatively wide horizontal cutter bar extending forwardly from said movable frame having a cutter chain movable thereabout, means for driving said cutter chain from said motor, a transversely extending direction changing member on the forward portion of said cutter bar within the vertical limits thereof, a plurality of laterally spaced wire mesh conveyors contained within the vertical limits of said cutter bar for a portion of its length and passing around said direction changing member, and means for driving said wire mesh conveyors from said motor.

6. In a mining and loading machine, a stationary frame, a movable frame slidably supported on said stationary frame for reciprocable movement therealong, a motor supported on said movable frame, plural speed means driven by said motor for reciprocably moving said movable frame along said stationary frame, a relatively wide horizontal cutter bar extending forwardly from said movable frame having a cutter chain movable thereabout, means for driving said cutter chain from said motor, a transversely extending direction changing member on the forward portion of said cutter bar within the vertical limits thereof, a wire mesh conveyor having a portion contained within the vertical limits of said cutter bar and passing around said direction changing member and another portion extending over said motor and beyond the rearward extremities of said mining and loading machine when said cutter bar is in its forwardmost position with re-

spect to said stationary frame, and means for driving said wire mesh conveyor from said motor.

7. In a mining and loading machine, a stationary frame, a movable frame slidably supported on said stationary frame for reciprocable movement therealong, a motor supported on said movable frame, plural speed means driven by said motor for reciprocably moving said movable frame along said stationary frame, a relatively wide horizontal cutter bar extending forwardly from said movable frame having a cutter chain movable thereabout, means for driving said cutter chain from said motor, a transversely extending direction changing member on the forward portion of said cutter bar within the vertical limits thereof, a plurality of laterally spaced wire mesh conveyors contained within the vertical limits of said cutter bar for a portion of its length and passing around said direction changing member, and another portion extending over said motor and beyond the rearward extremities of said mining and loading machine when said cutter bar is in its forwardmost position with respect to said stationary frame, and means for driving said wire mesh conveyors from said motor.

8. In a mining and loading machine, a stationary frame, a movable frame slidably supported on said stationary frame for reciprocable movement therealong, a motor supported on said movable frame, plural speed means driven by said motor for reciprocably moving said movable frame along said stationary frame, a relatively wide horizontal chain carrying cutter bar extending forwardly from said movable frame, and a wire mesh conveyor contained within the vertical limits of said cutter bar and extending over said stationary frame and beyond the rearward end thereof when said cutter bar and movable frame is in an extended position with respect to said stationary frame.

9. In a mining and loading machine, a stationary frame, a movable frame slidably supported on said stationary frame for reciprocable movement therealong, a motor supported on said movable frame, plural speed means driven by said motor for reciprocably moving said movable frame along said stationary frame, a relatively wide horizontal chain carrying cutter bar extending forwardly from said movable frame, a direction changing device supported within said cutter bar of less diameter than the thickness of said cutter bar, and continuous conveying mechanism mounted on said movable frame and having a portion contained within the vertical limits of said cutter bar and extending around said direction changing device and another portion extending over said stationary frame and beyond the rearward extremities thereof when said cutter bar is in its forwardmost position with re-

ter bar and movable frame is in an extended position with respect to said stationary frame.

10. In a mining and loading machine, a stationary frame, a movable frame slidably supported on said stationary frame for reciprocable movement therealong, a motor supported on said movable frame, a relatively wide horizontal chain carrying cutter bar extending forwardly from and movable with said movable frame and plural speed frictionally controlled gear reduction means driven by said motor for moving said movable frame and cutter bar along said stationary frame.

15. 11. In a mining and loading machine, a stationary frame, a movable frame slidably supported on said stationary frame for reciprocable movement therealong, a motor supported on said movable frame, a relatively wide horizontal chain carrying cutter bar extending forwardly from and movable with said movable frame and plural speed means driven by said motor for moving said movable frame and cutter bar along said stationary frame comprising a planetary gear reduction device.

20. 12. In a mining and loading machine, a stationary frame, a movable frame slidably supported on said stationary frame for reciprocable movement therealong, a motor supported on said movable frame, a relatively wide horizontal chain carrying cutter bar extending forwardly from and movable with said movable frame and plural speed frictionally controlled means driven by said motor for moving said movable frame and cutter bar along said stationary frame comprising a frictionally controlled planetary gear reduction device.

25. 40. Signed at Chicago, in the county of Cook and State of Illinois, this tenth day of April, 1980.

ALFRED B. ESSELTINE.
